US0D1099558S

(12) **United States Design Patent** (10) **Patent No.:** **US D1,099,558 S**
(45) **Date of Patent:** **** Oct. 28, 2025**

(54) **HAT RACK**

(71) Applicant: **Shenzhen Pengchengyueyi Technology Co., Ltd.**, Guangdong (CN)

(72) Inventor: **Mingpeng Yan**, Guangdong (CN)

(73) Assignee: **Shenzhen Pengchengyueyi Technology Co., Ltd.**, Shenzhen (CN)

(*) Notice: Patent file contains an affidavit/declaration under 37 CFR 1.130(b).

(**) Term: **15 Years**

(21) Appl. No.: **29/943,337**

(22) Filed: **May 21, 2024**

(51) LOC (15) Cl. **06-06**

(52) U.S. Cl.

USPC **D6/315**; D6/320

(57) **CLAIM**

The ornamental design for a hat rack as shown and described.

DESCRIPTION

FIG. 1 is a perspective view of a hat rack showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.

The broken lines depict portions of the hat rack and form no part of the claimed design.

1 Claim, 8 Drawing Sheets
